UNITED STATES PATENT OFFICE.

THOMAS J. McMAHON, OF BROOKLYN, NEW YORK.

DESIGN FOR A CURTAIN.

50,757.

Specification for Design.

Patented May 8, 1917.

Application filed October 27, 1916. Serial No. 128,137. Term of patent 3½ years.

To all whom it may concern:

Be it known that I, THOMAS J. McMAHON, a citizen of the United States, residing in the city of New York, borough of Brooklyn, county of Kings, and State of New York, have invented a new, original, and ornamental Design for a Curtain, of which the following is a specification, reference being had to the accompanying drawing, forming part thereof.

Figure 1 is a front view of a pair of curtains showing my new design.

Fig. 2 is an edge view of the curtains shown in Fig. 1.

I claim:

The ornamental design for a curtain, as shown.

THOMAS J. McMAHON.
